EMMA C. MAYNES, OF NORTH TONAWANDA, NEW YORK

FRONT FOR PLACE OF AMUSEMENT

Application filed September 26, 1931. Serial No. 565,248.

This invention relates to a front for a place of amusement particularly of the portable type carried by traveling shows, exhibitions, or carnivals.

5 In the case of traveling shows, the enclosure within which the exhibition is to be presented is customarily shielded from the view of the public by means of a "front" comprising a stationary canvas wall, or walls, upon 55 which are painted suitable decorations or representations calculated to appeal to the curiosity and imagination of the crowd, and having an entrance therethrough giving way to the enclosure. The vehicle by which the show 60

10 which is transported from place to place not infrequently is specially designed for use as the entrance way over the floor of which the patrons pass to enter the show, the canvas walls extending out from opposite ends of 65

15 the vehicle so as to flank the entrance.

The disadvantage of this type of front, however, is that, regardless of how highly emblazoned, it has become so commonplace as to attract little attention of itself and other 70

20 means must be resorted to in order to arouse the interest of the crowd; and this is particularly true where the show forms part of a carnival including a number of shows all 75

25 having fronts more or less alike and each competing against another for patronage.

The invention has for one of its objects 80

30 to provide a front which is novel to a point approaching the spectacular so as to catch and hold the eyes of passersby. To this end, 85

35 the front of the present invention contemplates the employment in place of the usual stationary canvas walls, or in conjunction with such stationary walls, of a traveling curtain or panorama, suitably decorated, and

40 having its ends connected together in the form of an endless belt wound over and driven between pairs of spindles. In the preferred form of the invention two such panoramic sections are located at opposite ends of 90

45 the vehicle so as to flank the entrance carried by the vehicle, the spindles over which the curtains are drawn being continuously rotated by a drive situated below the floor of 95

50 the vehicle. For the purpose of insuring a positive drive of the curtains, the curtains

are carried upon endless chains which engage suitable sprockets mounted on the spindles. Where the spindles are arranged to rotate about vertical axes, which construction ordinarily will be found most practicable, each 55 panoramic section includes a series of standards located at spaced intervals intermediate the pair of spindles, and supporting tracks along which trolleys connected to the chains are adapted to run, these trolleys serving to 60 hold the chains against sagging or buckling and to maintain the longitudinal runs of the curtain in a perfectly flat condition.

At night, or when weather conditions make it desirable, the ends of the curtain can be 65 disconnected and the curtains collapsed to out-of-the-way position. Since an important consideration of any traveling show is the compactness with which its paraphernalia may be stowed away while being carried from place to place and the facility with which it can be set up and knocked down on the lot, a further achievement of the invention is the provision of a portable front 70 of the type just described which is readily 75 transportable and capable of quick and easy assembly and disassembly. Thus, the spindles, tracks, track-supporting standards, curtains and chains may be quickly dismantled, the curtains rolled up on the spindles and all the parts loaded into the vehicle 80 when the show prepares to change its location.

In the accompanying drawings, I have illustrated a preferred embodiment of my invention. Figure 1 shows the front in elevation, the panoramic section on the left hand side of this figure being shown stripped of the curtain and borders, indicated in dotted lines, and disclosing the parts lying behind 85 the curtain; Figure 2 is a plan of Figure 1, a part of the floor of the truck being broken away to show the drive mechanism; Figure 3 is a vertical cross-section through the curtain, illustrating the manner in which the 90 curtain is supported upon the endless chains; Figure 4 is a fragmentary view of the panoramic section at the point of overlap of the two ends of the curtain and viewed from 95 behind the curtain; Figure 5 depicts a ban- 100

ner tower partially housing the drive spindle for traversing the curtain; Figure 6 is a top plan view of the banner tower of Figure 5; Figure 7 is a section on the line 7—7 of Figure 8 showing to better advantage the clutch for engaging the power-driven sheave with the spindle; Figure 8 shows in elevation the two connected end portions of the chain and the detaching device for coupling and uncoupling the ends of both the upper and lower chains; Figure 9 is a transverse section through the overlapped ends of the curtain; Figure 10 is a section on the line 10—10 of Figure 8 showing the means employed for retaining the detaching device against accidental displacement when the chains are coupled; Figure 11 is an enlarged view of spacer blocks carried by the trolleys shown in the position they occupy when the curtain is collapsed; and Figure 12 shows the front completely knocked down and loaded upon the vehicle.

In the preferred embodiment of the invention about to be described the front consists of three major parts, namely: a truck 1 and two panoramic sections 2 and 3, as shown in Figures 1 and 2. The truck 1 is of the same general type as is commonly used by road shows for transporting its paraphernalia from place to place and serving in addition as the entrance to the enclosure behind the vehicle where the entertainment is being offered. A skeleton frame covered by canvas or other sheet material forms an arch 4 extending longitudinally of the truck under which arch the patrons pass to enter the enclosure. Folding out from the side of the vehicle towards the exterior of the front is a platform 5 to which a pair of collapsible steps 6 leads. Another pair of steps, not shown in the drawings, leads down from the truck, usually from one or both its ends, into the enclosure.

The two panoramic sections 2 and 3 are in every essential respect alike so that a description of one will suffice as a description of the other. It may be stated that these sections are arranged at opposite ends of the vehicle so as to flank the entrance. While in the present embodiment the two sections are shown as extending in alinement, they might equally as well be arranged at an angle with respect to the entrance as may be determined by choice or by the particular conditions encountered at the place where a stand is made. Each panoramic section comprises a pair of spindles 8 and 9 located at opposite ends of the section around which the endless curtain travels. As best shown in Figures 5, 6, and 7, the drive spindle 8 is carried by a banner tower 10 comprising an elongated, open-work box structure adapted to be held in vertical position at the end of the truck by means of bolts engaging ears 11 projecting from the arch 4. The banner tower is open

upon its side opposite that contacting the arch 4 and extending parallel to this open side is the spindle 8 journaled in bearings 12 fastened to frames 14 located at the two ends of the banner tower. The weight of spindle 8 is borne by a ball thrust-bearing 15 (Fig. 7) interposed between a collar 16 fixed upon the spindle and the lower bearing 12. Similarly at the top of the spindle a collar 17 clamped thereon is supported upon a ball bearing 18 which in turn rests upon the upper spindle bearing 12.

The spindle 8 extends below the bottom of the banner tower and has loosely mounted thereon a drive sheave 19, this sheave bearing against a ring 20 immediately below it which is keyed to the spindle 8. A clutch 21 is provided for operatively connecting the sheave to and disconnecting it from the spindle 8. This clutch comprises a pair of holes 22 lying upon opposite sides of and extending parallel to the axis of ring 20, these holes opening into a pair of companion recesses 23 formed in the hub of sheave 19. Pins 22a, fixed in the end face of a sleeve 24 loosely surrounding the spindle below ring 20, are adapted to slide within the holes 22 and normally project up into the recesses 23 to lock the ring to the sheave. The pins are withdrawn from the recesses to disconnect the sheave from the spindle when the sleeve 24 is moved downwardly as by means of a hand-shifter 25 having a forked end embracing a circumferential groove on the sleeve 24. This clutch, as will later be explained, is designed primarily for use only when the curtain is being collapsed or the apparatus disassembled.

The two spindles 8 mounted in the banner towers located at opposite ends of the truck are driven by a cable 27 which extends between the sheaves 19 on the spindles. Supported upon a bench beneath the floor of the trucks is a motor 28, a drive wheel 29 operatively connected to the motor, and an idler pulley 30, an intermediate portion of the cable 27 being trained over the drive wheel so as to be frictionally driven thereby, and thence around the idler pulley as shown in Figure 2. A reduction gear box 31 is located between the motor 28 and drive wheel 29.

Keyed to the spindle 8 at appropriate distances from its upper and lower ends and partially housed within the banner tower 10 are a pair of sprockets 34 and 35, so that motion imparted to the spindle 8 by the sheave 19 will cause rotation of these sprockets. At the other end of the panorama section is the spindle 9 extending vertically up from a flat weighted base plate 37 which anchors it in place, this spindle having rotatably mounted thereon a pair of sprockets 38 and 39, companion to the sprockets 34 and 35 on spindle 8 and spaced a corresponding distance apart. An endless chain 40 extends

between the two upper sprockets 34 and 38 mounted on the spindles 8 and 9 respectively, and a similar chain 41 extends between the two lower sprockets 35 and 39, each chain 5 being composed of a train of links 42 (Figure 8) designed to engage the teeth of the sprockets and insure a positive drive.

The distance between the spindles 8 and 9 will of necessity be so great that unless support is afforded for the chains, they are likely to sway or sag under their weight, and in order to overcome this tendency the following provision is made: Spaced at approximately regular intervals between the spindles 8 and 9 are a series of standards 43 as illustrated in Figure 3, these standards being detachably held in predetermined spaced relation by cross-bars 52. The detachable cross-bars 52 may be of the type described in my Patent No. 1,674,734 of June 6, 1928. These standards comprise two parts, an upper pipe section 44, constituting the major length of the standard, and a short stub section 45 arranged to telescope within the lower end of the pipe section. The stub section 45 extends vertically up from a flat base plate 46 and is provided with a plurality of transverse openings 47 spaced a short distance apart, each adapted to receive a cotter pin 48 which projects on both sides beyond the circumference of the section. The lower end of the pipe section 44 is enlarged and formed on diametrically opposite sides with corresponding right-triangular slots 49, the edge of each slot forming the hypotenuse of the triangle being stepped or notched as shown in the figure, so that by inserting the cotter pin 48 through a suitably selected opening 47 and turning the base plate to bring the projecting ends of the cotter pin into engagement with an appropriate notch of the slot, a fairly nice vertical adjustment of the standard may be attained to compensate for irregularities in the ground level on which the front is erected.

Rigidly fastened to the pipe section 44 are an upper cross-arm 50 and a lower cross-arm 51. The lower cross-arm 51 adjacent its ends and at equal distances from the pipe section 44 carries bearing blocks 53 each having a beveled under surface 54 and also a flat upper surface provided with an outwardly disposed lip 55 on the end of the block nearest the standard 44. Upon these blocks are supported I-beams 56 having welded upon their bottom faces attaching elements 57 shouldered along their outer edges whereby one shoulder may be inserted under the lip 55 and the other engaged by a clip 58 clamping over the outer end of block 53. As the clip is tightened upon the block as by means of a bolt, the tapered under surface 54 of the block draws the attaching element into firm seating engagement with the flat upper face of the block.

The upper cross-arm 50 is similarly provided at its opposite ends with bearing blocks 53a engaging attaching elements 57a welded to I-beams 56a and having clips 58a for securing the rails to the bearing blocks, this structure being identical with that provided on the lower cross-arm 51, except that instead of the I-beam resting upon the bearing blocks as in the case of the lower cross-arm, the I-beams are held suspended by the bearing blocks so that the I-beams extend in alignment one above the other with their free sides disposed toward each other, as shown in Figure 3.

The I-beams 56 and 56a carried by the series of standards 43 together make up upper and lower tracks 60 and 61 respectively, occupying positions a short distance above and below the straight runs of the chains 40 and 41. For maintaining the track sections 80 in registry, upon the flat under faces of the I-beams and overlapping their ends are fastened plates 63 having complementary tongue and slot portions, as indicated in Figure 4, so that the tongue on the end of one I-beam 85 will snugly fit within the slot on the contiguous end of the adjacent I-beam. On the banner tower 10 located above and below the paths of the chains where they wind over the sprockets 34 and 35 on the spindle 8 are 90 permanently mounted arcuate sections of track 64 and 65; and similarly supported upon cross-arms 62 (Fig. 1) carried by the spindle 9 above and below the sprockets 38 and 39, are arcuate track sections 66 and 67. These arcuate track sections at their ends unite with the straight portions of track 100 leading between the spindles 8 and 9 whereby to form two complementary tracks extending in closed paths corresponding to those of the chains 40 and 41.

Connected to the chains 40 and 41 and adapted to roll along the upper and lower tracks 60 and 61 are a series of trolleys 72 each having a forked end spanning the free or unattached side of the I-beams. On the opposed faces of the legs of the forks are rotatably mounted a pair of axially aligned rollers 68 having their treads contacting with the inner surfaces of the flanges of the I-beam. The trolleys are arranged at equal and suitably spaced intervals throughout the length of the tracks and corresponding trolleys of the two tracks are connected for unitary movement by means of vertical stays 69. The stays are detachably fastened to the trolleys by means of upper and lower stay cotter pins 69a and 69b. To these stays is attached the panoramic curtain 71 by permanent fasteners 70, the stays serving as a backing to maintain the straight runs of the curtain in flat condition. The curtain is preferably of one piece, (or a number of pieces sewed together) one of the two ends of the curtain, 125 130

having a flap 73, as shown in Figure 9, adapted to overlap and button onto its other end after the curtain has been wound over the two spindles 8 and 9 in the process of setting 5 up the front.

The point where the two ends of the curtain are united is so chosen that it corresponds to the place where the two chains are arranged to be disconnected. To simultaneously uncouple the upper and lower chains there is provided the following detaching device: Upon an ear 75 projecting from a stay 69 is pivotally attached an operating bar 76, and at equal distances upon opposite sides 10 of its pivot are in turn pivoted rods 77 and 78. These rods are of equal length and connected at their extremities to coupling pins 79 and 80 which are slidable within guiding lugs 82 and 83 on the stay 69. The pins 82 15 and 83 extend through and serve to unite two adjacent links 42 of each chain 40 and 41. When the operating bar 76 is swung about its pivot to the dotted line position shown in Figure 8, the coupling pins 79 and 80 are 20 withdrawn from the links uncoupling both chains. To latch the coupling pins in operative position, the lower end of the operating bar 76 is formed into an arcuate seat 80 as shown in Figure 10, so as to normally embrace 25 a side of the rod 78 when the operating bar 76 is in parallelism with the rod 78. The pivot connection of the rod 78 to the operating bar 76 is sufficiently loose, however, so that the rod 78 may be sprung outward to 30 clear the sides of the arcuate seat when the detaching device is operated. As shown in Figure 8 the disconnected links of each of the two uncoupled chains are both supported 35 upon separate trolleys. This is for permitting the ends of the chains to be readily united by drawing the two trolleys together which action brings the corresponding ends 40 of each chain in approximate registry and the coupling can be easily effected.

45 As will later be explained, when the curtain is to be collapsed, or the entire front dismantled—as from time to time it must be either because of high winds or when moving to a new location—the ends of the chains are 50 disconnected in the manner just described and the trolleys are run along the tracks so as to bunch them together into a compact string, the sections of chains extending between adjacent trolleys being allowed to loop 55 or fold loosely in a lateral direction. In order to maintain the trolleys from canting and binding on their tracks as otherwise might happen when the chains become slack, a spacing block 84 as shown in Figs. 8 and 60 11 is attached to each of the trolleys. The spacing blocks of the train of trolleys lie in alignment, and each block is provided at one end with a tapered nose 85 and at its other end with a corresponding tapered recess 86. 65 As the trolleys are run together when the

curtain is collapsed, the nose 85 on the end of one block fits into the recess 86 on the reverse end of the adjacent block as shown in Figure 11, so that the string of trolleys is maintained rigid which prevents their tipping and binding on the tracks.

In order to conceal the tracks and trolleys from view so as to lend an attractive appearance to the front, the outer run of the panoramic curtain, that is, the run of the curtain which is exposed to the view of the public, is overlapped at its upper and lower marginal edges by borders 90 and 91, as shown in Figure 3. These borders are made of canvas fastened to flexible cables 92 extending along their rear or unexposed faces and disposed in slightly spaced relation thereto adjacent their edges. To afford intermediate support for the borders, upon the end of each of the standards 43 adjacent the outer run of the curtain—that is, that portion of the curtain being presented to public view—is clamped a vertical bar 93 and this bar at each end has formed side-by-side thereon a pair of oppositely directed hooks 94. In setting up the front, the cable 92 may be snapped under these hooks and then drawn taut between suitable retaining means which holds the borders from sagging. The borders ordinarily extend only along the side of the front exposed to the view of the public and their arrangement and design will be largely a matter of choice. A central facing member 97 for uniting the two adjacent ends of the top borders 90 is 100 mounted above the arch.

In transporting the show from one locality to another, it is desirable that the curtain be rolled up in a compact manner. Therefore, before the panoramic section is completely dismantled the curtain is wound on a hollow drum 95 (Figs. 5 and 7). The drum 95 is carried upon a pair of spaced spools 96 which freely rotate on the spindle 8 with the lowermost spool which sustains the weight of the drum resting upon a ball bearing 98 seating against the hub of sprocket 35. A pair of pins 99 on the drum may be engaged at the beginning of the winding operation with the cotter pin holes in the ends of the stays 69 carried by the curtain, and a flange 100 of slightly less diameter than the sprocket 35 and located at the lower end of the drum provides a guide and supporting plate for the lower end of the stays 69 supporting the curtain during winding.

As has been previously pointed out, both panoramic sections are of identical construction and therefore require no separate description. The invention may be embodied in many different forms. For example the curtains may be constructed to travel in either vertical or horizontal paths, and in either event the path of travel of the curtain may be straight on the side presented to the

view of the spectators, or may be undulated, and any number of panoramic sections may be employed. Furthermore, many of the features which are incorporated in the preferred embodiment described above may be omitted without departing from the invention. Especially is this true of the knock-down and collapsible construction described which may be employed or dispensed with as desired.

When the front has been erected, it will be apparent that operation of the motor 28 located under the floor of the truck 1, will drive the cable 27 in the direction indicated by the arrows in Fig. 2, thus winding of this cable over the sheaves 19 which will impart rotation in opposite directions to the spindles 8. This will drive the chains 40 and 41 extending between sprockets 34 and 35 on spindle 8 and 20 idler sprockets 38 and 39 mounted on spindle 9, and the series of trolleys 72 supporting the intermediate sections of the chains will follow along the upper and lower tracks 66 and 67. The two curtains carried upon the outer 25 runs of the chains of the two panoramic sections will thus travel in opposite directions and toward the entrance way. The stationary borders 90 and 91 skirting the upper and lower edges of the exposed face of the curtains 30 constitute in effect a frame for the decorations continuously being brought into view by the moving curtain. Whenever it is desired to stop the movement of the curtain for any reason a switch (not shown) 35 may be opened to cut off the current to the motor 28.

At night or because of unfavorable weather conditions, the curtains may be collapsed to protect them from injury. When the curtain 40 is collapsed it is desirable that equal portions of the curtain of each panoramic section shall lie upon opposite sides of the spindle 8. As a preliminary step, therefore, the clutch 21 is operated by the hand-shifter 25 to disengage the spindle 8 from the drive sheave. This permits the curtain to be easily drawn along by hand until the disconnectible links of the chains lie at the point A (Fig. 2) just clearing the idler sprockets 38 and 39 on sprindle 9. The overlapped ends of the curtains are unbuttoned to provide access to the detaching device which is operated in the manner previously described to uncouple the two disconnectible links of the upper and 55 lower chains. The trolleys supporting the straight outer run of the chain A-B may now be collapsed within the limits B-C, the spacing blocks 84 preventing jamming of the trolleys on the tracks as they are bunched together and rolled along the tracks.

The spindle 9 is next rotated in the opposite direction until the other ends of the upper and lower chains which were located at A are now located at E clear of the sprockets 38 and 39, this reverse rotation of spindle

9 transmitting, through the uncollapsed straight inner runs of the chains, reverse movement to the spindle 8 which feeds equal amounts of the chains to the collapsed section B-C. The length of chain E-F is now collapsed into the limits F-G. Due to slippage between the cable 27 and the sheaves 19, the disconnectible links of the chains of each panoramic section cannot be relied upon to lie at corresponding points in their endless paths when the apparatus is stopped even though they originally may have occupied such position at the beginning of the drive, so that if the disconnectible links of one panoramic section upon stopping the curtain should occupy position A, very probably the disconnectible links on the other panoramic section would occupy a different position. Consequently the primary purpose of the clutches 21 is to free the spindles 8 from their drives so as to allow each panoramic section to be independently manipulated to bring the disconnectible links of each pair of chains to the proper points for uncoupling.

When the device is to be moved to a new location, the entire front must be dismantled. The upper and lower borders are first removed by disconnecting the ends of the cables and detaching their intermediate portions from the hooks 94, after which the borders may be rolled up into compact bundles. The curtain 71, to which is permanently fastened the stays 69, is detached from the lower chain 41 by removing the lower stay cotter pins 69b. The canvas curtain with stays attached is wound onto drum 95 while it is in perpendicular position, this being done by first pulling out the cotter pins 69b on the lower part of the curtain and as the chains are moved to advance the curtain toward the drum, the upper stay cotter pins 69a near the drum are pulled out. After the chains have been collapsed, the clips 58 fastening the I-beam sections to the blocks 53 may be released and the I-beam sections, together with the chains 40 and 41, removed. The cross-bars 52 connecting the standards 43 and spindles 9 are next detached and these standards, together with the spindle 9, knocked down. After folding up the platform 5 and collapsible steps 6, the front will have been completely dismantled, and all the parts will be loaded onto the vehicle, as shown in Figure 12, for transportation to a new location.

I claim:

1. In a portable front for a place of amusement, a vehicle, an entrance carried by the vehicle, panoramas extending on either side of the entrance each comprising an endless curtain, vertical spindles about which the curtains move, supports for the curtains between the spindles, and a drive carried by the vehicle for rotating one of the spindles of

each panorama to continuously traverse the curtains.

2. In a portable front for a place of amusement, a vehicle, an entrance carried by the vehicle, panoramas extending on either side of the entrance each comprising an endless curtain, vertical spindles about which the curtains move, supports for the curtains between the spindles, a drive carried by the vehicle for rotating one of the spindles of each panorama to continuously traverse the curtains, means for reeling up the panorama curtains on the spindles and means for knocking down the curtain supports and stowing them and the reeled curtains in the vehicle.

3. A front for a place of amusement comprising an entrance, panorama curtains extending on either side of the entrance each comprising an endless curtain, vertical spindles about which the curtains move, and a drive for rotating one of the spindles of each panorama to traverse the outer run of each curtain toward the entrance.

4. A panorama for a place of amusement comprising a pair of spaced vertical spindles, an endless curtain extending around the spindles, rails between the spindles, trolleys carried by the curtain movable over the rails, sprockets on the spindles, a chain on the curtain engaging the sprockets, means for rotating one of the spindles to traverse the curtain, means for disconnecting the ends of the curtain whereupon the curtain, chain and trolley can be collapsed, and means for holding the trolleys in alignment when the curtain is collapsed.

5. A panorama for a place of amusement comprising a pair of spaced vertical spindles, an endless curtain extending around the spindles, rails between the spindles, trolleys carried by the curtain movable over the rails, sprockets on the spindles, a chain on the curtain engaging the sprockets, means for rotating one of the spindles to traverse the curtain, means for disconnecting the ends of the curtain whereupon the curtain, chain and trolley can be collapsed, and spacing blocks carried by the trolleys for holding the trolleys in alignment when the curtain is collapsed.

50 6. A panorama for a place of amusement comprising a pair of spaced vertical spindles, an endless curtain extending around the spindles, rails between the spindles, trolleys carried by the curtain movable over the rails, sprockets on the spindles, a chain on the curtain engaging the sprockets, means for rotating the spindles to traverse the curtain, means for disconnecting the ends of the curtain, and means for disengaging the trolleys 60 and chains from the curtain, whereupon the curtain can be reeled upon one of the spindles.

7. A panorama for a place of amusement comprising a pair of spaced vertical spindles, an endless curtain extending around the spindles, spaced vertical stays secured to the cur-

tain, a chain connecting the stays, rails between the spindles, trolleys mounted on the chain engaging the rails, sprockets on the spindles meshing with the chain, means for rotating the sprockets to traverse the curtain, means for disconnecting the ends of the curtain so that it may be collapsed comprising a slideable pin connecting two end links of the chain, and means mounted on an adjacent stay for withdrawing the pin.

8. A panorama for a place of amusement comprising a pair of spaced vertical spindles, rails between the spindles, an endless curtain extending around the spindles, spaced vertical stays secured to the curtain, an endless chain secured to the upper ends of the stays, a second endless chain secured to the lower ends of the stays, trolleys mounted on the chains engaging the rails, sprockets on the spindles, meshing with the chain and means for rotating the sprockets to traverse the curtain.

9. Means for disconnecting the ends of the curtain as claimed in claim 8 so that it may be collapsed, comprising slideable pins connecting two links of each chain, and means mounted on an adjacent stay for simultaneously withdrawing both pins.

In testimony whereof I affix my signature.
